UNITED STATES PATENT OFFICE.

HENRY B. BURCKHART, OF CHICAGO, ILLINOIS, ASSIGNOR TO YAWMAN & ERBE MANUFACTURING COMPANY, OF ROCHESTER, NEW YORK, A CORPORATION OF NEW YORK.

INDEX-TAB.

1,079,209.

Specification of Letters Patent. Patented Nov. 18, 1913.

Application filed October 25, 1907. Serial No. 399,094.

To all whom it may concern:

Be it known that I, HENRY B. BURCKHART, a citizen of the United States of America, and resident of Chicago, Cook county, Illinois, have invented a certain new and useful Improvement in Index-Tabs, of which the following is a specification.

My invention relates to improvements in index tabs, especially of that kind which are removable and adjustable, and has for its object the production of a device that may be readily placed on any thickness of paper without tearing the same.

A further object is the production of a device that may be adjustably locked in place, so as to be irremovable except by the application of unusual force.

A further object is the production of a device whereby the gripping tension of the springs, fixing the tab or clip in place, may be adjusted.

A further object is the production of a device that can be cheaply manufactured, and one that will best serve the purposes for which it is intended.

These and such other objects as may hereinafter appear are attained by my device, embodiments of which are illustrated in the accompanying drawings, in which--

Fig. 1 represents a perspective view of my improved tab or clip in place on a page. Fig. 2 represents views in elevation of the elements shown in Fig. 1 disassembled. Fig. 3 represents a vertical sectional view through the center of the device illustrated in Fig. 1. Fig. 4 represents a plan view of a metallic blank from which the body of the tab is formed. Fig. 5 represents a perspective view of my compression band or lock. Fig. 6 represents a perspective view of another form of my compression band or lock.

Like numerals of reference indicate like parts in the several figures of the drawing.

Referring now to the drawing, 7 represents a metallic blank of spring metal having two openings therein 8-9, with oppositely disposed cut-away portions 10-11. The openings 8-9 are so placed that the sides thereof register when the blank is folded through the center. The vertical edges of the metal formed at the ends of the cut-away portions register when the blank is folded in the center, forming shoulders 12-13 on the wing members. The blank is formed with oppositely raised portions

14-15, the latter forming pronounced shoulders 16-17, best shown in Figs. 2 and 3. One end of the blank is curved inwardly, forming a flange 18.

Referring now to Fig. 5, this represents a compression band or spring lock 19, having its central portion cut away at 20 and folded upon itself forming two spring sides 21-22.

In Fig. 6, I have illustrated another form of a compression band or spring lock, in which, for the sake of lightness, a portion of the metal from one of the sides is cut away.

23 represents a strip of blank paper or other suitable material whereon an inscription or title may be written or printed. Where I use printed index characters or letters I do the printing on smooth surfaced paper, then dip in a chemical solution, then lay a thin sheet of transparent celluloid over the printed side and adhere them together by a heated roller.

Referring now to the operation and assembling of my device, the tab is normally in the position shown in Fig. 2 at *a*, with the members slightly sprung apart. The index member is inserted between the sides, and the tab passed over the edge of the sheet 29 of the paper or book on which it is intended to be secured. The tab is pushed on just far enough so that the shoulders 12-13 register with the edge of the leaf. The compression band is then slipped over the end and over the raised portion 14, and brought into engagement with the shoulders 16-17, thus forcing the sides of the tab or clip tightly together, the end 24 of the underside forcing the paper tightly against the flange 18, thus gripping it securely in position, the back portions 25-26 of the compression band fitting closely against the shoulders and leaf, thus insuring the proper positioning of the tab and the holding of the same in position.

The two raised portions 14-15 form a spring stop, preventing the compression band or lock from slipping off while the shoulders 16-17, in addition to forming a stop for the band, also serve to raise the body of the clip on a level with the band itself. This is quite an important feature in my device, as the leaves in turning are forced to slide over the clip, and in the event that the compression band projected above the surface of the clip the leaves would catch thereon and be apt to become bent or torn.

When large clips are required, the weight of the metal becomes quite an important element, as it will be readily noted that the placing of twenty-six or more metal clips on the leaves of a book increases considerably its weight and bulkiness. For this reason, I prefer to use another form of the compression band or lock shown in Fig. 6. In this form, a portion of one side is cut away, leaving projecting ears 27-28 to serve in place of one side. I find that these ears possess sufficient gripping force to hold the tab securely in place, while at the same time the weight of the device itself is materially decreased.

The compression band is in itself practically a spring clip having members 21-22 by the adjustment of which the gripping force of the tab as a whole may be regulated. It will be noted that these members normally tend to meet if extended, consequently fit closely on the tab.

One of the other difficulties in the proper construction of index tabs has been that of providing sufficient room for the index character, as well as sufficient gripping width without making the tab of undue width. The cutting away of the center of the compression band at 31 makes it possible to fit the band closely against the shoulders, and at the same time permits the use of a narrow band.

It will be noted that when the device is not in place, there will be a small opening between the flange and the end 24 of the lower member, thus permitting the slipping of the tab on the leaf, regardless of the thickness or texture thereof. This is a distinct improvement over the tabs of which the old form of tabs on the leaf, unless the paper is quite thick or hard, there is great danger of tearing the leaf. At the same time it was necessary to have the leaf under considerable tension in order that the tab may not slip off the leaf after it is in place. For this reason they are more liable to be pulled off the leaf in the ordinary handling of the book. By the use of my device, however, the members of the tab are not under tension before being placed on the leaf, and consequently can be readily placed thereon, the tension or gripping force being obtained by the use of the compression band after the tab is in place.

It will be readily seen that by varying the shape of the flanged end and the compression band any degree of gripping force may be attained, so that the tab will be held in place even to the extent of tearing out a portion of the leaf before it will let go its

hold. Of course, it is understood that it is not expected that the gripping force will be so great when the paper is of a finer or softer texture, as, of course, it is not desired to have the tab tear the leaf, but the statement above is made to show the possibility of adjusting the tab within any reasonable degree. I further believe I am the first to combine with a label holder or index tab formed from two members each embodying a label holding portion and a supporting portion, a movable compression device which cooperates with the two members to force the latter together to hold a label between the label holding portions and to grip a support by the supporting portions.

Of course other modifications of the tab may be made, but any of them that include the adjustability of the gripping means or tension come within the spirit of my invention.

I claim:

1. A label holder or index tab comprising two members each embodying a label holding portion and a supporting portion, and a removable compression device engaging both of the two members to force them together in order to hold a label between the label holding portions and to grip a support by the supporting portions.

2. A label holder or index tab comprising two members connected together to swing relatively to each other and each embodying a label holding portion and a supporting portion, and a compression device cooperating with the two members to force them together in order to hold a label between the label holding portions and to grip a support by the supporting portions.

3. A label holder or index tab comprising two members each embodying a supporting portion and a label holding portion, one of the latter being provided with an opening for the exposure of the index or label, and a removable band constituting a compression means located and engaging with both members between said portions to hold a label between the label holding portions and a support between the supporting portions.

4. A label holder or index tab comprising a pair of gripping jaws and a pair of label holding portions formed from a single piece of sheet material folded on itself and provided with an index exposure opening, the fold being located on one side of the exposure opening and detachable means for holding, respectively, both the two label holding portions and the gripping portions together located on the opposite side of the exposure opening.

5. A label holder comprising two members each embodying a label holding portion and a supporting portion, said members being resiliently connected together, and exteriorly arranged movable compression

- means coöperating with the outer faces of both members between the label holding portions and the supporting portions to force the members together.
- 5 6. An index tab comprising an index holding means and a pair of gripping members having portions presenting converging faces when pressed together, and a compression member movable on the index holding 10 means into and out of engagement with the outer converging faces of the gripping members.
- 15 7. An index tab comprising a pair of members connected by a fold at one of their ends, having converging free ends, and shoulders between the free ends and the fold, the pair of members being formed from a single blank of sheet material recessed on opposite sides to provide the shoulders and 20 bent between its ends to provide the two members, and a compression member adapted to fit over the folded end and coöperate with the shoulders to hold the free ends against separation.
- 25 8. An index tab comprising two integral opposed parts each embodying a gripping member formed at one end with index holding means adapted to embrace an index member and having an opening for the exposure of the index, one of said parts having a pair of fixed angular shoulders extended from opposite sides thereof to aline with the marginal edge of material to which it is attached.
- 30 9. An index tab comprising integral gripping members formed at one end to embrace an index member and having an opening for the exposure of the index and at the other end with angular shoulders adapted to aline 35 with the marginal edge of material to which it is attached and as stops for a compression member, and a compression band engageable over the first-named end and adapted to engage said shoulders to compress said gripping members.
- 40 10. An index tab comprising a member folded upon itself and having alined openings, oppositely disposed shoulders and gripping ends, and a compression member engageable over the said member and forming a stop for the material to which said tab is to be attached.
- 45 11. An index tab comprising a folded member for embracing an index member and having alined openings for the exposure thereof, inner shoulders adjacent the inner margins of said openings and laterally extended wings with converging ends, and a compression band engageable over the portion with alined openings and having portions engageable over said wings and compressing the free ends of said folded member.
- 50 12. An index tab comprising spring members having openings to expose an index member held therebetween and provided with two pairs of oppositely disposed shoulders, and spring means for yieldingly holding said members in operative relation with each other, sail holding means comprising a metallic spring clip folded on itself and having converging sides and adapted to pass over one pair of shoulders and abut against the second pair, thus locking said holding means in operative position.
- 55 Signed by me at Chicago, Illinois, this 22nd day of October, 1907.
